UNITED STATES PATENT OFFICE.

FRANK MOUSLEY, OF MORTLAKE, LONDON, ENGLAND.

FACE-POWDER BOX OR CONTAINER.

1,370,833.

Specification of Letters Patent.

Patented Mar. 8, 1921.

Application filed December 23, 1920. Serial No. 432,767.

To all whom it may concern:

Be it known that I, FRANK MOUSLEY, a subject of the King of England, residing at Priest Bridge, Mortlake, S. W. 14, in the 5 county of London, England, whose post-office address is Priest Bridge, Mortlake, S. W. 14, in the county of London, England, have invented certain new and useful Improvements in and Relating to Face-Powder 10 Boxes or Containers, of which the following is a specification.

This invention relates to face-powder boxes or containers of the kind described in the specification of my United States Patent 15 No. 1,355,412.

The object of the present invention is to produce a powder box or container of the indicated type provided with two compartments so as to be adapted to two different 20 kinds of material, for example, ordinary face-powder and a coloring material, such as rouge cosmetic.

In the accompanying drawings:—

Figure 1 is a top plan view of my im- 25 proved face-powder box or container;

Fig. 2 is a section taken on the line 2—2 in Fig. 1; and

Fig. 3 is a bottom plan view of same.

The box or container A consists of two 30 annular pieces *a* and *a'* of some soft pliable or flexible material, such as leather or rubber, sewn or otherwise secured together at *c* and divided into two compartments by a partition piece of some flexible material *d* secured to one or both of the annular pieces. 35 Each annular piece is provided with an aperture or mouth *b*, *b'*.

The powder-puff comprises a foundation or back B, also made of soft pliable or flexible 40 material, on to which foundation or back the fur, swansdown, or other loose texture puff material B² is secured in any well-known manner.

The cosmetic-applying device D consists 45 also of a backing of soft pliable or flexible material, on to which backing the cosmetic-

applying material D², of any suitable kind, is secured.

The back B of the puff and the back of the cosmetic-applying device D are made of 50 the shape of, and slightly larger than, the apertures or mouths *b* and *b'* respectively of the annular parts of the container so as completely to close said mouths when the puff and device are inserted in the container 55 as shown in Fig. 2. The puff and cosmetic-applying device are each provided with a loop or other handle, B' and D' respectively, by which they can be inserted into and withdrawn from their respective compartments 60 in the container A.

C in Fig. 2 represents face-powder in a receptacle in the container, but the powder may, if so desired, be placed loose in the 65 container.

Obviously both compartments may be used for face-powder or for cosmetic or other similar material, if so desired.

Having fully described my invention what I claim and desire to secure by Letters Patent is:—

A combined face-powder container and a powder puff, said container being made of 75 flexible or pliable material in the shape of a flat bag, a partition in said container dividing it into two compartments, a central aperture or mouth in each compartment of the container, a puff for each compartment having a back made of flexible or pliable material and larger than the respective 80 apertures or mouths in the container and shaped so as entirely to close the respective apertures or mouths of the powder container when inserted therein.

In testimony whereof I have hereunto set 85 my hand in presence of two subscribing witnesses this 6th day of December, 1920.

FRANK MOUSLEY.
